UNITED STATES PATENT OFFICE.

GLEN M. DYE, OF MINNEAPOLIS, MINNESOTA.

METHOD AND APPARATUS FOR HANDLING PHOTOPRINTS.

Application filed August 25, 1924. Serial No. 733,987.

This invention relates to a method and apparatus for developing and washing photographic or similar prints. It is a common practice for amateurs who take kodak and other pictures to take the films to a commercial developing and printing establishment to have the prints developed and finished. Such establishments now in the large cities handle a large amount of such business and the volume of this business varies greatly from day to day and week to week. In certain periods during the summer the volume will be large and at other periods the volume will be quite small. It is difficult for the developing and printing establishment, therefore, to properly regulate the number of employes for handling the work. If a sufficient force is maintained to handle the work during a week of large volume the same force will not be kept busy during a week when the volume of business is small and the establishment will thus have a heavy pay roll for which it receives no return. It is quite a desideratum therefore to provide an automatic or mechanical means for handling the prints during the developing, fixing and washing stage as well as during the drying or glazing stage. With such a mechanical means, once the developing and printing establishment has invested in the same, it can take care of a large or small volume of business without any change in its operating force. The invention also has great utility in regular commercial studio establishments where large quantity production is desired, especially where a large number of prints are made from one plate or film.

It is an object of this invention, therefore, to provide a method by means of which the photographic prints can be developed, rinsed, fixed and washed while being progressed through a machine and without the help of any considerable number of operators.

It is another object of the invention to provide a method consisting in progressing the prints, face up, on a conveyor and successively spraying on said prints, developing, rinsing, fixing and washing solutions, the said solutions being kept separate and separately collected after being used.

It is further an object of the invention to provide a method consisting in supporting the prints face up upon a stationary

member and successively lifting, progressing 55 and depositing the prints thereon, said prints and said member being simultaneously and successively sprayed with developing, rinsing, fixing and washing solutions.

It is still another object of the invention 60 to provide a method of finishing photographic prints which consists in progressing the same face up, successively spraying thereon, developing, rinsing, fixing and washing solutions and in continuing said 65 progression to the receiving means of a print drying or print drying and glazing device.

It is a still further object of the invention to provide an apparatus for finishing photographic prints which comprises a conveyor 70 on which the prints are disposed face upward and progressively moved having thereabove a plurality of means for successively spraying on the prints developing, rinsing, fixing and washing solutions. 75

It is still further an object of the invention to provide a print finishing apparatus comprising a stationary member having a surface for supporting the prints face upward together with means for successively lifting, 80 advancing and depositing the prints on said surface, and means above said surface for successively spraying on said prints and surface developing, rinsing, fixing and washing solutions. 85

It is also an object of the invention to provide a print finishing apparatus comprising a plate adapted to support the prints thereon face upward and having a plurality of apertures therethrough and a plate disposed beneath said plate substantially parallel thereto having means projecting upward therefrom adapted to be projected through said apertures, together with means for transmitting motion in a curved path to 90 said last mentioned plate to cause said means to move through said apertures successively to lift and advance and deposit said plates on said surface.

It is still another object of the invention 100 to provide an apparatus, as set forth in the previous paragraph, in which the last mentioned plate has a plurality of discharge apertures for discharging the various fluids, both of said plates preferably being inclined 105 upwardly whereby the fluids will drain downwardly thereon, together with receptacles for receiving the various fluids.

It is still further an object of the invention to have such an apparatus as above set forth delivering the prints to a conveyor which conveniently may be the receiving conveyor of a drying or drying and glazing machine.

These and other objects and advantages of the invention will be fully set forth in the following description made in connection with the accompanying drawings in which 10 like reference characters refer to the same parts throughout the different views, and in which.

Fig. 1 is a view in side elevation of an apparatus for carrying out the method of 15 the invention;

Fig. 2 is a top plan view of said apparatus;

Fig. 3 is a vertical section taken substantially on the line 3—3 of Fig. 1, as indicated by the arrows;

Fig. 4 is a vertical section taken on the line 4—4 of Fig. 3, as indicated by the arrows;

Fig. 5 is a partial view in plan of a print 25 supporting plate;

Fig. 6 is a partial plan view of the conveyor plate; and

Fig. 7 is also a partial plan view of the print supporting plate, Figs. 3 to 7 being 30 shown on an enlarged scale.

Referring to the drawings, an apparatus is shown comprising a frame having spaced vertical members 8, horizontal members 9 and upwardly inclined longitudinally spaced members 10. Supported by the longitudinal members 10 and extending lengthwise of the apparatus in an upwardly inclined position is a print supporting plate 11 conveniently carried by spaced members 12 secured to the members 10. The plate 11, as clearly shown in Fig. 3, has vertically extending side portions, thus forming in effect a trough and said member also has rows of spaced elongated slots or apertures 13 extending therethrough throughout substantially its entire length. As shown in Fig. 1, said plate is divided into different zones by short downwardly extending portions 14. In the first zone, which is at the lower end 40 of the device, said plate is provided with an opening extending some distance longitudinally thereof which is traversed by spaced wires 15, the spaces between said wires extending longitudinally in alignment with the slots 13. Disposed below the plate 11 and extending substantially parallel thereto is another plate 16. The plate 16 is divided into a plurality of zones or sections and the adjacent ends of these sections are preferably offset, as shown at 17 in Figs. 1 and 4. The portions 17 correspond substantially to the zone defining portions 14 in the plate 11. It will be noticed, as shown in Fig. 4, that the forward ends of the sections of 45 plate 16 are slightly upturned. The plate

16 is imperforate and has projecting upwardly therefrom series of rows of pins 18, which pins are centrally aligned with and spaced similarly to the slots 13 in the plate 11 so that the said pins may be projected 70 through the slots 13, the pins being of somewhat smaller diameter than the width of said slots. The plate 16 has depending ears 19 at each side thereof, adjacent the offset portions or openings 17, which ears receive 75 crank pins projecting inwardly from crank disks 20, said crank disks being supported upon shafts 21 journaled in bearings secured to the top of the frame members 10, which shafts are driven by a series of chains 22 80 running over sprockets secured to said shafts. The shaft 21 at the lower end of the plate is driven by a chain 23 running over a sprocket secured to a jack shaft 24 journaled in bearings supported on a pair of the 85 frame members 9, which jack shaft is, in turn, driven by a chain 25 running over a sprocket thereon and over a sprocket secured to a suitable driving motor 26 illustrated as of the electrical type, which motor is conveniently supported on the horizontal members 9 of the frame. A conveyor 27 is supported on bearings secured to the frame members 10 and adapted to receive prints from the 90 upper end of the plate 11.

Disposed above each zone of the print supporting plate 11 is a spraying device, said device being designated 28, 29, 30 and 31, respectively. Each of said spraying devices comprises a conduit extending longitudinally at one side of the plate 11 and substantially parallel therewith, which conduit has a plurality of conduits or pipes 32 extending at right angles therefrom and across the plate 11 above the same. Each of the pipes 32 is provided with a controlling valve 32a adjacent the conduit to which it is secured and each of said pipes is provided with a plurality of perforations on its underside. The spraying device 28 is supplied with liquid through pipe 33 having a valve 34 therein, which pipe communicates with a container 35, the pipe 33 communicating with the longitudinal conduit of sprayer 28. Receptacle 35 also has a pipe 38 communicating therewith and extending downwardly to the outlet of a pump 37 illustrated as of the rotary type. The inlet side of pump 37 communicates through a pipe 38 with a receptacle or tank 39 so disposed that it receives any liquid flowing down over the lower section of plate 16. The pump 37 conveniently is driven by a chain 40 running over a sprocket on its operating shaft and over a sprocket on the jack shaft 24. The tank 39 and container 35 are adapted to contain developing fluid, which fluid is sprayed by the spraying members 28. The spraying member 29 is adapted to spray water and has its longitudinally extending 110

conduit supplied by a pipe 41 equipped with a valve 42, which pipe will be connected to any suitable water supply, such as the ordinary city supply line. The spraying device 30 has its longitudinally extending conduit supplied by a pipe 43 equipped with a valve 44.

The pipe 43 communicates at its upper end with a container 45. Containers 35 and 45 are surrounded by tanks 60 and 61, respectively, adapted to receive cooling water, and which also contain pipes 62 and 63 by which a temperature regulating medium, such as steam may be supplied to regulate the temperature of the liquids in said containers. The container 45 also has a pipe 46 communicating therewith and extending downward to the discharge outlet of a pump 47 also shown as of the rotary type and as having its inlet end connected by a pipe 48 with a tank 49. The pump 47 conveniently is driven by a chain 57 running over a sprocket on its operating shaft and over a sprocket on the jack shaft 24. The tank 49 is adapted to receive liquid flowing down and discharged from the lower end of the lowest section but three of plate 16. The pipes 38 and 48 are each equipped with a valve controlled drain pipe 50 which may be connected to the sewer or other convenient discharge means. A tank 51 is also provided adapted to receive the liquid flowing down and discharging from the lowest section but one of plate 16, said tank having a discharge pipe 42 connected thereto which may direct the liquid from said tank into a sewer or other suitable sink. The spray device 31 has its longitudinally extending conduit supplied by a pipe 53 having a controlling valve 54 therein, which pipe will be connected to any suitable water supply, such as the ordinary city supply line. A tank 55 is provided adapted to receive from the upper section of plate 16, which tank is also provided with a discharge pipe 56 leading to the sewer or other suitable discharge location.

Preferably, the tanks 39 and 49 have strainers 58 disposed adjacent their tops onto which the liquid discharged into said tanks is received.

In carrying out the method of the invention by the use of the apparatus disclosed, power will be supplied to the jack shaft 24 through motor 26 and pumps 37 and 47 will be driven. The shafts 21 will also be driven at each side of the machine and rotary motion imparted to the cranks 20 successively from said shaft through the chains 22. The plate 16 will thus be given a rotary motion in a closed curved path, as indicated by the dotted circle *b* in Fig. 4. The upper end of each pin 18 will thus be carried upwardly into and partly through its corresponding aperture 13 and will then

be withdrawn downwardly through said aperture. The proper developing fluid will be supplied in container 35, the proper water connections made to pipes 41 and 53 and a fixing solution supplied in container 35. The valves in the pipes 33, 41, 43 and 53 will now be opened, as will also be valves 32. The operator will be positioned at the lower end of the apparatus and will lay prints which have just been printed onto the lower end of plate 11. These plates will be immediately deluged with the developing fluid discharged downwardly from the pipes 32 of sprayer 28. As the plate 16 is moved and the pins projected upward through plate 11 the prints will be lifted on the tops of these pins and carried forwardly thereby. As the pins recede downwardly through the openings the prints will again be deposited on the surface of plate 11. This action is continuously repeated and the prints are progressively advanced upward on plate 11, being lifted and laid down repeatedly. The pins 18 also project upwardly between the wires 15 and lift and carry the prints upwardly along said wires in the same manner. The operator will watch the prints as they develop. The image thereon comes up and if necessary, will lift the prints from the wires 15 and again place them on the plate 11 at a lower point. The wires 15 are provided for convenience in picking up the prints. The operator can place his fingers beneath the wires and readily engage the print by the edge. If the prints were picked up by passing the fingers through the slots 13 the operator would be in danger of having his fingers pinched by the pins 18. By thus retarding some of the prints and advancing others necessary the prints are all brought to the proper stage of development as they pass through the lower zone of plate 11. The developing fluid runs through the plate 11 down onto the plate 16, it being noted that the lower end of plate 11 is upturned to prevent any fluid running off its lower edge. The developing fluid runs down plate 16 and off the lower end thereof into tank 39 which extends some distance rearward of said edge. The fluid runs through the strainer 57 where any dirt, paper lint or other foreign matter is strained therefrom. From the tank 39 the fluids are again raised and delivered to tank 35 by the pump 37. The developing operation, therefore is continuously carried on and the operator only will have to place the prints on the lower edge of the plate 11 and possibly to retard or advance some of the prints. The prints will be printed a certain time, in accordance with the density of the film, so that with the vast majority of prints no adjustment on the plate 11 will be necessary. The speed of the plate 16 will be properly regulated

to give the desired developing effect. One or more of the pipes 32 can also be thrown out of operation, if desired, by manipulation of the valve 32^a. The prints thus advance on the plate 11 and will next be sprayed by the water issuing from the pipes 32 of sprayer 29 so that the developing fluid will be well washed therefrom and the prints thus thoroughly rinsed.

10 It will be found that there is an intimate co-operation between the advancing means for the prints, as shown, and the spraying means. If the prints were advanced on a moving plate 6 and were continuously kept 15 in contact with the surface thereof some developing fluid might adhere to the lower side of the print. By repeatedly lifting the print, and laying it down on the fluid on top of plate 11, the thorough washing of the print is insured and the water is applied to both sides thereof. The rinsing water passes through plate 11 and drains off of the second section of plate 16 into tank 51, from 20 which it is directed through the pipe 52. The print continues to advance on plate 11 and then comes under the spraying device 30 which deluges the print with a fixing 25 solution. This fixing solution runs through the plate 11 and drains from the third section of plate 16 into the tank 49. In entering tank 49 it passes through one of the strainers 58 so that any dirt, paper lint or other foreign material is strained therefrom. From the tank 49 the fixing solution is again 30 raised to container 45 through pipe 46 by the pump 47 so that the discharge of the fixing solution from the spraying device 30 is continuous. The developing and fixing 35 solutions may, of course, be replenished when exhausted by draining the tanks 39 and 49 by means of the pipes 50 and supplying a new batch of solution to containers 35 and 45. It will be noted that the fixing solution 40 is prevented from running back onto the second zone of plate 11 by the downwardly inclined portion 14. It will also be noted, as clearly shown in Figs. 1, 2 and 4, that there is no spray pipe close to the portions 45 of plate 11 at the upper side of said portions. The fluids sprayed therefore cannot engage a print bridging portion 14 so that fluid could run from one zone to the next lower zone on such a print. By the 50 time the print reaches the first spray pipe above portion 14 it is in position to shed water downwardly on the inclined portion 14 or is altogether past said portion. The print now advances on plate 11 and comes under the washing sprayer 31 and is 55 thoroughly washed by the water issuing from the pipes 32 thereof. The washing water gets on both sides of the print owing to the fact that the print is repeatedly lifted and deposited on plate 11. The washing liquid drains down the upper section of 60

plate 16 into tank 55 from which it is discharged through pipe 56. The print is discharged upwardly off the edge of plate 11 and discharged onto the conveyor 27. Conveyor 27 may be the receiving conveyor of 70 any suitable drying apparatus which may take the form of that disclosed in applicant's prior Patent 1,277,202, granted August 27, 1918, or it may take the form of a print drying and glazing apparatus disclosed in the co-pending application of 75 James W. Passman, filed December 5th, 1923, S. N. 678,697 assigned to the Pako corporation, of which applicant is the 80 president.

In the above described method and operation, therefore, the print is continuously advanced and successively sprayed by the developing, rinsing, fixing and washing 85 fluids. These fluids being separately collected and prevented from any intermingling, the prints finally being discharged directly onto the drying apparatus.

From the above description it is seen that applicant has provided a very efficient 90 method and apparatus for mechanically handling and finishing photographic prints. The apparatus can be run at different speeds and has a capacity for handling a very 95 large number of prints. The machine may also be made in various widths, according to the capacity desired. With such an installation, a print finishing establishment can conveniently handle a varying volume 100 of business without taking on additional help.

The entire action of the apparatus after a print of normal exposure has been placed thereon is automatic and the prints need not be handled by the operator until after 105 the same are ready for sorting and delivery to the customer. The parts of the machine are comparatively few and simple. The machine is easily made and installed and requires practically no attention for maintenance. The apparatus has been thoroughly 110 demonstrated in actual practice and found to be very successful and efficient.

The expression "face upward" in the 115 claims is to be taken as including any print with its image side disposed away from the conveyor or supporting member whether the print is in flat or inclined position.

It will, of course, be understood that various changes may be made in the form, 120 details, arrangement and proportions of the parts and in the various steps of the method without departing from the scope of applicant's invention which, generally stated, consists in a method and apparatus capable 125 of carrying out the objects above set forth, such as shown and described and defined in the appended claims.

What is claimed is:

1. The method of finishing separate cut 130

- photo prints which comprises progressing said prints face upward on a conveyor, and successively spraying on said prints developing and rinsing fluids.
- 5 2. The method of finishing photo prints which comprises progressing said prints face upward on a conveyor, successively spraying on said prints developing, rinsing, fixing and washing fluids and separately collecting said fluids after engagement with said prints and conveyor.
- 10 3. The method of finishing photo prints which consists in intermittently supporting and progressing said prints face upward upon a stationary member, and successively spraying on said prints developing, rinsing, fixing and washing solutions while supported and progressed on said member.
- 15 4. The method set forth in claim 3, with the added step of separately collecting said fluids and preventing any intermingling thereof.
- 20 5. The method of handling photo prints which consists in placing said prints face upward upon a stationary support, successively lifting, advancing and depositing said prints upon said support, and successively spraying upon said prints and support, developing, rinsing, fixing and washing fluids whereby said prints are contacted on both sides by said fluids.
- 25 6. The process of finishing separate cut photo prints which consists in progressing said prints face upward, successively bringing said prints into contact with developing, rinsing, fixing and washing fluids, and delivering said prints to a drying apparatus.
- 30 7. An apparatus for handling photo prints having in combination, a conveyor for supporting and intermittently advancing said prints face upward, and means for spraying a developing fluid on said prints.
- 35 8. The structure set forth in claim 7, and means for subsequently spraying said prints with a rinsing fluid while supported and intermittently progressed on said conveyor.
- 40 9. An apparatus for handling separate cut photo prints having in combination, a conveyor for supporting and advancing said prints face upward, means above said conveyor for spraying a developing fluid on said prints, means for successively spraying a rinsing fluid on said prints, and means beyond said last mentioned means in the direction of advance of said print for spraying a fixing solution on said prints.
- 45 10. The structure set forth in claim 9, and means for spraying a washing fluid on said prints subsequently to the spraying of said last mentioned means.
- 50 11. An apparatus for finishing photographic prints having in combination, means for supporting a print face upward, means for successively lifting, advancing and depositing said prints on said means, and means for spraying a developing fluid on said prints and first mentioned means.
- 55 12. The structure set forth in claim 11, and means for subsequently spraying a rinsing solution on said prints while still supported on first mentioned means and advanced by said second mentioned means.
- 60 13. The structure set forth in claim 11, and means for subsequently successively spraying on said prints while still supported and advanced fixing and washing solutions.
- 65 14. An apparatus for finishing photographic prints having in combination, a member on which said prints are supported and progressed face upward, means above said member for successively spraying on said prints developing, rinsing, fixing and washing solutions, and means co-operating with said member for separately collecting said fluids and preventing intermingling thereof.
- 70 15. An apparatus for finishing photographic prints comprising a stationary plate adapted to support a print face upward thereon having elongated spaced apertures therethrough, a plate below said plate having pins projecting upwardly therefrom aligned with and spaced similarly to said apertures, means for moving said last mentioned plate in a closed path to project said pins through said apertures to engage, lift, advance and deposit said prints successively on said first mentioned plate, and means for successively spraying a plurality of fluids on said prints and first mentioned plate.
- 75 16. The structure set forth in claim 15, said last mentioned plate having a discharge means for each of said fluids, means for straining said fluids, and means for separately collecting said fluids.
- 80 17. An apparatus for finishing photo prints having in combination, an upwardly inclined plate adapted to support prints and having spaced apertures therethrough, a plate beneath said plate substantially parallel thereto and carrying means spaced similarly to said apertures and adapted to be projected therethrough, means for moving said last mentioned plate for projecting said means through said apertures successively and lifting, advancing and depositing said prints on said first mentioned plate, means extending across said first mentioned plate for successively spraying a plurality of fluids on said prints and first mentioned plate, said second mentioned plate having openings therethrough for discharging each fluid separately.
- 85 18. A print treating apparatus having in combination, means for supporting and advancing a print face upwardly, a plurality of spaced means for successively spraying developing, rinsing, fixing and washing fluids respectively on said prints in said

first mentioned means, means for separately collecting fluids and means, adapted to deliver the prints to a drying mechanism, for receiving the prints from said first mentioned means.

19. An apparatus for finishing photo prints having in combination, a stationary member on which a print is supported face upward, means for successively raising, advancing and depositing said print on said member, means for successively spraying said print with developing and rinsing fluids.

20. The structure set forth in claim 19, and means for subsequently and successively spraying on said print fixing and washing fluids, and means for separately collecting all of said fluids.

21. An apparatus for finishing photo prints having in combination, a stationary member having a surface adapted to support a print face upward and having rows of apertures therethrough, a member beneath said member movable in an endless path having means thereon projecting through said apertures and engaging, lifting, advancing and depositing said prints successively on said surface, and means for successively spraying said prints and surface with a plurality of different fluids.

22. An apparatus for finishing photo prints having in combination, an upwardly inclined perforated plate having a surface adapted to support a print, means for repeatedly lifting and advancing said print along said plate, a liquid container supported above said plate, a spraying device disposed over said plate for spraying said liquid on said print and plate and connected to said container, control means for said sprayer, a tank into which said sprayed liquid is received, and means for returning said liquid from the tank to said container.

23. An apparatus for finishing photo prints having in combination an upwardly inclined perforated plate, said plate being divided into a plurality of zones, a liquid sprayer device for each zone disposed over said plate, means for advancing a print on said plate, control means for said sprayers, and means for receiving the sprayed liquids.

24. The structure set forth in claim 23, said first mentioned means comprising a plate beneath said first mentioned plate and having corresponding zones and a discharge means for each zone, and adapted to receive the sprayed liquid from said first mentioned

plate and direct the same to said receiving means.

25. A print developing machine having in combination, a frame, a motor thereon, a jack shaft driven from said motor, a pump driven from said jack shaft, a tank connected to the inlet of said pump, a liquid container connected to the outlet of said pump, an upwardly inclined plate on said frame, means for lifting and advancing a print upwardly on said plate, a sprayer disposed over said plate and connected to said container, said tank receiving the sprayed liquid.

26. The structure set forth in claim 25, and means for regulating the temperature of the liquid in said container.

27. The method of finishing a photo print, which consists in supporting a print wholly by gravity on a surface, intermittently lifting said print from and advancing the print along said surface, and successively spraying said print with a plurality of finishing fluids.

28. The method of finishing photo prints which comprises progressing said prints face upward on a conveyor, and successively spraying on said prints developing, rinsing, fixing and washing fluids.

29. The method of handling separate cut photo prints which consists in supporting said prints, face upward, on a member, successively lifting said prints from and advancing the same relatively to and depositing the prints on said member, and successively spraying on said prints and member a plurality of print treating liquids.

30. An apparatus for treating separate cut photo prints having in combination, a member on which said prints are supported, face upward, and movable means for repeatedly lifting said prints from said member, advancing the same relatively to said member and again depositing the same on said member, and means for successively spraying on said prints and member a plurality of print treating liquids.

31. An apparatus for handling photo prints having in combination, a perforated plate, said plate being divided into a plurality of zones, a liquid spraying device disposed respectively over said zones, means for advancing a print on said plate, and means for separately receiving the liquids sprayed from said spraying devices.

In testimony whereof I affix my signature.
GLEN M. DYE.
